UNITED STATES PATENT OFFICE

2,476,753

LOAD HOLDING DEVICE

Howard W. Miller, Durham, N. C.

Application December 15, 1947, Serial No. 791,793

2 Claims. (Cl. 280—179)

1

The present invention relates to new and useful improvements in load holding devices, and more particularly to means for holding barrels, hogsheads, drums and the like when loaded horizontally in pyramidal form against longitudinal sliding or shifting movement while being transported in railway cars, trucks or other vehicles.

An important object of the invention is to provide quick detachable means between the ends of the stacked barrels which firmly holds the uppermost as well as the lowermost barrels rigidly to each other to prevent longitudinal shifting movement of one relative to the other.

A further object of the invention is to provide a load holding device of this character which includes end plates positioned at the ends of the stacked barrels and connected to each other by a chain or cable together with means whereby the plates may be tightened against the ends of the barrels in clamping engagement therewith and whereby the device may be carried in a compact form for easy handling, when not in use.

A still further object is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view of horizontally stacked barrels or drums with parts broken away and shown in section and showing the load holding device in position thereon.

Figure 2 is an end elevational view.

Figure 3 is an enlarged front elevational view of the chain tightening drum.

Figures 4 and 5 are enlarged vertical sectional views taken respectively on the lines 4—4 and 5—5 of Figure 3, and

Figure 6 is a perspective view of the rear holding plate.

Referring now to the drawings in detail, wherein for the purpose of illustration I have disclosed a preferred embodiment of the invention, the numeral 5 designates a front holding plate of substantially triangular form having a pair of horizontally spaced apart bearing plates 6 suitably secured to its front surface and in which the shaft ends 7 of a drum 8 are journaled.

2

A toothed wheel or ratchet 9 is secured to one end of the shaft 7 and a lever 10 is pivoted on the shaft adjacent the ratchet. A dog 11 is pivoted on the lever to engage the teeth of the ratchet to rotate the drum 8 by movement of the lever in one direction.

A second toothed wheel or ratchet 12 is secured to the opposite end of shaft 7 and with which a pivoted pawl or dog 13 is engageable to hold the shaft and drum against reverse rotation.

A chain 14 is secured at one end to a bolt and nut 15 at one of the flanges of the drum 8 and extends through an opening 16 at the central portion of the plate 5.

The other end of the chain 14 is attached to a horizontal bar 17 on the rear surface of a rear plate 18 likewise of substantially triangular shape.

The front plate 5 is formed at its upper edge with a rearwardly projecting flange 19 and the rear plate 18 is formed at its upper edge with a forwardly projecting flange 20.

In the operation of the device the plates 5 and 18 are placed at the opposite ends of a group of hogsheads, barrels, drums or the like as indicated at 21 stacked horizontally in pyramidal form in a manner commonly employed for transporting the hogsheads on the bed 22 of a railway car or truck and with the sides of the stacked hogsheads held against lateral rolling movement by chocks 23.

The flanges 19 and 20 are hooked over the rim 24 of the upper hogsheads or barrels 25 to support the front and rear plates thereon and the chain 14 is extended under the upper hogshead or row of hogsheads, as the case may be, and attached to the bar 17 of the rear plate 18 by a suitable collar or clevis 26. The chain is then wound on the drum 8 by lever 10 to tighten the chain and thus clamp the plates 5 and 18 at the opposite ends of the load whereby the upper, as well as the lower hogsheads are prevented from longitudinal movement.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein

described and the scope of the appended claims.

Having described the invention, what is claimed as new is:

1. A load holding device for hogsheads and similar containers stacked horizontally in pyramidal form, said holding device comprising a pair of plates positioned at the ends of the containers in bridging engagement with a plurality of the containers, and means connecting the plates to each other and holding the containers against relative endwise movement, said means comprising a drum journaled on one of the plates, a flexible member windable on the drum and connected to the other of said plates, and a manually operable ratcheting device for the drum.

2. A load holding device for preventing relative endwise movement of hogsheads stacked horizontally with the highest one resting on two lower ones, said device comprising a pair of triangular plates relatively smaller than the ends of the hogsheads and opposed against the ends of the same at opposite ends of the stack, one of said plates having an aperture therein, a straight

corner flange on each plate hooking over the rim of the highest hogshead at the bottom thereof and suspending said plates from said rim in overlapping relation to the rims of the lower hogsheads, and means operable to draw said plates together into clamping relation to the rims of the hogsheads comprising a cable wind-up drum on the apertured plate parallel with the corner flange of the plate, and a wind-up cable extending from said drum through said aperture and connected to the other plate.

HOWARD W. MILLER.
